Primary Examiner — Justin M Jonaitis*Assistant Examiner* — Holly M Rodriguez(74) *Attorney, Agent, or Firm* — Sierra IP Law, PC;
 William K. Nelson(57) **CLAIM**

The ornamental design for a joint finder as shown and described.

DESCRIPTION

FIG. 1 is a perspective view of an embodiment of the joint finder with the proximal end of the joint finder positioned in an upward position;

FIG. 2 is a side view of a first side of the joint finder of FIG. 1;

FIG. 3 is a side view of a second side of the joint finder of FIG. 1;

FIG. 4 is a side view of a third side of the joint finder of FIG. 1;

FIG. 5 is a side view of a fourth side of the joint finder of FIG. 1;

FIG. 6 is a view of the distal end of the joint finder of FIG. 1;

FIG. 7 is a view of the proximal end of the joint finder of FIG. 1; and,

FIG. 8 is an enlarged, detailed view of the portion of the joint finder circled in FIG. 1.

The broken lines in the drawings illustrate portions of the Joint Finder which form no part of the claimed design.
